BLOUSE

Pauline A. Landert, St. Louis, Mo.

Application February 17, 1950, Serial No. 144,680

7 Claims. (Cl. 2—196)

1

This invention relates in general to wearing apparel and more particularly to a lady's blouse.

The primary object of the present invention is to provide a lady's blouse having associated therewith a removable and reversible auxiliary panel with its faces of contrasting colors, or of different materials, or ornamented in different manners in order to provide the wearer with a change.

It is a further object of the present invention to provide a blouse having associated therewith a reversible auxiliary panel which incorporates collar-forming members designed to furnish the wearer with a fresh and clean appearing collar in whichever position the panel may be used and which will be of the material of the opposite face to present an attractive contrast.

It is an additional object of the present invention to provide a blouse having associated therewith a reversible auxiliary panel which may be easily formed from a variety of patterns.

It is a further object of the present invention to provide a blouse having associated therewith a reversible auxiliary panel which may be economically fabricated and which may be readily adapted to conform to current fashions.

With the above and other objects in view, my invention resides in the novel features of form, construction, arrangement, and combination of parts presently described and pointed out in the claims.

In the accompanying drawings (two sheets)—

Figure 1 is a front view of a blouse constructed in accordance with and embodying the present invention;

Figure 2 is a back view;

Figure 3 is a front view of the blouse;

Figure 4 is a front view of the reversible auxiliary panel, showing one corner thereof turned back;

Figure 5 is a fragmentary front view illustrating a reversible auxiliary panel having a modified type of collar;

Figure 6 is a fragmentary back view of the modified type collar;

Figure 7 is a front view of the blouse having disposed thereon a modified type reversible auxiliary panel;

Figure 8 is a fragmentary back view;

Figure 9 is a front view of the modified type auxiliary panel;

Figure 10 is a front view of the blouse having disposed thereon the modified reversible auxiliary panel with a further modified type of collar; and

2

Figure 11 is a back view.

Referring now to the drawings, which illustrate preferred embodiments of the present invention, A designates a combination blouse comprising a main or body-portion B formed of front and rear panels 1, 2, marginally seamed together, and being provided with a collar-less neck opening 3 and armholes 4.

Provided for removable disposition upon the central portion of the front panel 1 is an auxiliary panel 5 extending substantially from the shoulders to the waist thereof, having upper or shoulder margins 6, 6', substantially aligned with the shoulder portions of the blouse A and a lower transverse margin 7 substantially aligned with the bottom margin of the blouse A. Said panel 5 is fabricated of two thicknesses of material to provide faces 8, 9, which preferably are designed to present different appearances. As shown in Figure 4, for purposes of illustration, the face 8 is relatively dark while the face 9 is of lighter color in contrast therewith. Obviously, the faces 8, 9, can be made of different fabrics, each having its own particular pattern, or said faces 8, 9, may, if desired, be ornamented or decorated as by embroidery, beading, and the like. The combination of designs and appearances which may be effected thereby are myriad. The panel 5 is laterally contoured to provide a series of points 10 with the lower lateral margin vertically disposed to provide a generally rectangular base section 11. Integrally provided in the auxiliary panel 5 and projecting upwardly from the shoulder margins 6, 6', is a pair of wing members 12, 12', having inner margins 13, 13', respectively, which are upwardly and outwardly inclined, and converge at their lower ends which are continued a short distance into the body of said panel 5 to form a V opening, as at 14. The upper edges 15, 15', of said wing members 12, 12', incline downwardly and outwardly to tab-like points 16, 16', respectively, formed by the meeting of the upper edges 15, 15', and outwardly and upwardly inclined outer margins 17, 17', respectively. Provided adjacent the tab-like points 16, 16', are buttonholes 18, 19, respectively, said buttonhole 18 extending substantially transversely, while the buttonhole 19 extends in substantial parallelism with the outer margin 17' for purposes appearing more fully hereinafter.

For attachment to the blouse A the auxiliary panel 5 is provided with a plurality of buttonholes 20 disposed adjacent the points 10, the upper corners of the base section 11, and upon

the shoulder margins 6, 6', adjacent the wing members 12, 12'. Said buttonholes 20 are adapted for engagement with buttons 21 sewed or otherwise suitably mounted upon the front panel 1 of the blouse A as may be seen in Figure 3. Secured to the rear panel 2 adjacent the central portion of the rear margin of the neck opening 4 is a button 22 for engagement with the buttonholes 18, 19, of the wing members 12, 12'. It is, of course, apparent that the attaching means herewith presented could be easily supplanted by snap-fasteners, hooks and eyes, and any other suitable expedients.

In usage, the auxiliary panel 5 is affixed to the front panel 1 of the blouse A by means of the buttons 21 and buttonholes 20. Thereon the wings 12, 12', are led rearwardly over the shoulders of the blouse A and brought together in collar-forming relationship by overlapping disposition of the tab-like points 16, 16', upon the button 22 on which the buttonholes 18, 19, are engaged, with the axes thereof being in substantially normal relation to assure that the collar thereby formed will lie smoothly and attractively. With the points 16, 16', thus secured, the wings 12, 12', are folded or turned outwardly exposing the opposite facing 8 or 9 as the case may be, to provide a fashionable collar of contrasting appearance to the outwardly presented body portion of the auxiliary panel 5. As shown in Figures 1 and 2, the collar formed by the wings 12, 12', is fashioned to present points in the rear and an oval-like appearance forwardly. In attached position, the base section 11 of the panel 5 extends transversely across the waist portion of the blouse A and thereby anchors panel 5 against any untoward upward-riding tendency. It will thus be seen that by means of the auxiliary panel 5 the wearer is provided with a ready change so that should one face of the panel 5 become soiled it may be easily reversed. If the wearer were to wear a suit jacket, only the auxiliary panel 5 would appear and hence by reversal thereof it would seem that the wearer did possess numerous blouses. As presented in the various figures, the blouse A is shown to be sleeveless. However, it is apparent that said blouse A may have short sleeves or long sleeves as the wearer may elect. Furthermore, said panel 5 may be provided with any lateral contours desired, the pointed contour herein presented is merely illustrative of one particular style into which the auxiliary panel 5 may be patterned.

If desired, an auxiliary panel 5' may be provided for engagement upon the blouse A, having the same lateral contour as the auxiliary panel 5 and buttonholes 20' for engagement with the buttons 21 of said blouse A. Integrally formed with, and projecting upwardly from, the upper portion of the panel 5' is a pair of wing members 23, 23', having spaced inner margins 24, 24', the lower ends of which extend into the body of the auxiliary panel 5' and incline outwardly being connected by a transverse seam 25 to form a truncated V opening 26 when the wings 23, 23', are in collar-forming position.

Similar in all respects to the tab-like points 16, 16', of the wings 12, 12' above described, the wings 23, 23', are provided with tab-like points 21, 27, respectively, having suitable buttonholes for engagement upon the button 23 of the blouse A. It will thus be seen that with the panel 5' in attached position upon the blouse A, wings 23, 23', provide an attractive, more open-type collar (see Figures 5 and 6).

If desired, a modified type auxiliary panel 28 may be provided having contrasting facings 8', 9', and comprising substantially symmetrical lateral sections 29, 29', which are stitched together along their inner vertical margin in the formation of a center seam 30. Each of said sections 29, 29', is provided with a shoulder margin 31, 31', and a lower transverse margin 32, 32', respectively, in substantial alignment with the shoulder portions and bottom margins of the blouse A, respectively. The outer margins of the sections 29, 29', slope inwardly and downwardly to a point spaced from the lower margins 32, 32', respectively, hence said outer margins extend transversely outwardly and then downwardly to form a base portion 33. Integrally formed with each section 29, 29', and extending upwardly from the respective shoulder margins 31, 31', thereof, is a wing member 34, 34', respectively, having inner portions 35, 35', which are offset from the center seam 30 in mutual lapping relationship, as may be seen in Figure 9. Said wings 34, 34', are provided with tab-like points 36, 36', having buttonholes 37, 37', respectively which are in all respects similar to the tab-like points 16, 16', and buttonholes 18, 19, hereinabove described in connection with the auxiliary panel 5, for engagement with the button 22 of the blouse A. The auxiliary panel 28 is also provided with a plurality of symmetrically disposed buttonholes 38 for engagement with the buttons 21 of the blouse A. When the panel 28 is attached to the blouse A, the wings 34, 34', will form an attractive, relatively full, pointed collar 39, which may be rounded in the back as shown in Figures 7 and 8.

The style of the auxiliary panel 28 may be easily adapted to present various styles of collars such as the modified type shown in Figures 10 and 11, wherein an auxiliary panel 28' may be provided with wings 40, 40', the inner portions 41, 41', of which lap in less degree than the wings 34, 34', above described, and are rounded to present the type collar commonly known as a "Peter Pan," when said wings 40, 40', are secured upon the button 22 of the blouse A in collar-forming relationship.

It should be understood that changes and modifications in the form, construction, arrangement, and combination of the several parts of the blouse may be made and substituted for those herein shown and described without departing from the nature and principle of my invention.

Having thus described my invention, what I claim and desire to secure by Letters Patent is:

1. A blouse comprising a front panel, a back panel, a plurality of buttons being provided on said front panel and a single button provided on said back panel, a reversible auxiliary panel having facings of different appearance, said auxiliary panel being provided with a plurality of buttonholes for engagement with the buttons on the front panel, wing members provided on said auxiliary panel and projecting upwardly therefrom, said wing members being each provided with tab-like portions having buttonholes for engagement upon the button provided on the back panel, whereby in engaged position the tab-like portions will be in overlapping relationship causing said wings to be disposed in collar-forming position wherein the free portions of said wings may be turned outwardly to present the reversed face.

2. A reversible auxiliary panel for use with blouses and the like comprising faces of different appearance, said panel having shoulder margins

and a lower transverse margin, and wing members integrally formed with said panel and projecting upwardly from the shoulder margins, said wings having inner margins which extend into said panel to form an opening therein, said wing members being further provided in their outer portions with tab-like elements, said tab-like elements having means for securement to a blouse in lapped relationship, the inward portions of said wings being adapted for outward folding to expose the reverse face of the panel when said panel is in either of its wearing positions.

3. A woman's blouse comprising a body portion having a collarless neck-opening, a front panel provided on its outer face with fastening elements, said fastening elements being arranged in two rows on opposite sides of the front panel, an auxiliary panel disposed in flatwise overlying relation on the outer face of the front panel and being removably held in place by said fastening elements, said auxiliary panel having a pair of collar forming elements adapted to encircle the neck-opening, and fastening means at the rear of the neck-opening for securing the ends of said collar-forming elements to each other and to the body portion.

4. A blouse comprising a front panel, a back panel, fastening elements provided on said front panel and a fastening element provided on said back panel, a reversible auxiliary panel provided with cooperative fastening means for engagement with the fastening elements on the front panel, wing members provided on said auxiliary panel and projecting upwardly therefrom, said wing members being each provided with tab-like portions having co-operative fastening means for engagement upon the fastening element provided on the back panel whereby in engaged position the tab-like portions will be in overlapping relationship causing said wings to be disposed in collar-forming position wherein the free portions of said wings may be turned outwardly to present the reversed face.

5. A reversible auxiliary panel for use with blouses and the like comprising a body portion, and wing members integrally formed with said body portion and projecting upwardly therefrom, said wing members having inner margins which extend into the body portion to form an opening therein, said wing members being further provided in their outer portions with tab-like ele-

ments, said tab-like elements having means for securement to a blouse in lapped relationship, the inward portions of said wing members being adapted for outward folding to expose the reverse face of the body portion when said panel is in either of its wearing positions.

6. A woman's blouse comprising a body portion having a collarless neck-opening, a front panel provided on its outer face with fastening elements, an auxiliary panel disposed in flatwise overlying relation to the outer face of the front panel and being removably held in place by said fastening elements, said auxiliary panel having a pair of collar-forming elements adapted to encircle the neck-opening, and fastening means at the rear of the neck-opening for securing the ends of said collar-forming elements to each other and to the body portion.

7. A reversible auxiliary panel for use with blouses and the like comprising a body portion consisting of symmetrical sections secured to each other along one of their lateral margins to form a meeting line extending upwardly from the bottom of the panel, wing members provided on said body portion and projecting upwardly from each section thereof, each of said wing members having inner portions which project in opposite directions beyond the meeting line so that said wing members are normally in lapped relation to each other, said wing members being further provided in their outer portions with tab-like elements, said tab-like elements having means for securement to a blouse in lapped relationship, the inner portions of said wing members being adapted for outward folding to expose their reverse facing when said panel is in either of its wearing positions.
